FIREARM CONSTRUCTION

David M. Williams, New Haven, Conn., assignor
to Western Cartridge Company, New Haven,
Conn., a corporation of Delaware

Application February 4, 1942, Serial No. 429,448

2 Claims. (Cl. 42—75)

The present invention relates to improvements in firearm structures and relates more particularly to means for absorbing recoil shocks between the receiver and the complemental stock of a given firearm.

One of the objects of the present invention is to provide a firearm structure having a superior construction and arrangement of parts whereby the connection of a receiver and a stock is of such character as to minimize or eliminate the splitting of the stock occasioned by recoil shocks or stresses incident to the discharge of the firearm.

Another object of the present invention is to provide a superior firearm construction wherein means is provided adjacent the receiver-cavity in a stock for holding the walls of such cavity or recess from spreading under recoil stresses and without requiring the use of transverse screws or the like.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1 is a view of the central portion of a firearm structure embodying the present invention and shown partly in side elevation and partly in vertical central-longitudinal section;

Fig. 2 is a horizontal sectional view taken on the line 2—2 of Fig. 1;

Fig. 3 is a transverse sectional view taken on the line 3—3 of Fig. 1;

Fig. 4 is a broken view in vertical central-longitudinal section of the central portion of the stock;

Fig. 5 is a top or plan view thereof;

Fig. 6 is a view in side elevation of the trigger-plate member detached;

Fig. 7 is a top or plan view thereof; and

Fig. 8 is a broken underside view of the receiver-member detached, together with a portion of the barrel.

The particular firearm herein chosen for purposes of illustrating one form which the present invention may assume, comprises in the main a stock 10, a receiver-unit 11 and a barrel 12. The said stock 10 is preferably made of wood or other suitable heat-insulating material and the receiver-unit 11, in the instance shown, comprises a receiver-member 13 and a trigger-plate mem-

ber 14. Both of the members 13 and 14, as well as the barrel 12, are preferably formed of high-grade steel.

The two complemental members 13 and 14 of the receiver- or frame-unit 11 may be secured together in any suitable manner such, for instance, as by providing the receiver-member 13 in the lower portion of its hollow interior with a pair of longitudinally-extending coupling-ribs 15—15 laterally spaced apart and projecting respectively inwardly toward each other from the respective opposite side-walls of the member 13, as is especially well shown in Fig. 3. Resting respectively upon the upper surfaces of the coupling-ribs 15—15 just referred to are coupling-ribs 16—16 projecting outwardly respectively in opposite directions from the opposite sides of a lug 17 upstanding from the trigger-plate member 14 about midway the length thereof.

20 The lower portion of the receiver-member 13 and the major portion of the trigger-plate member 14 is normally accommodated in a vertical longitudinal recess 18 formed in the stock 10 before referred to, and intersecting both the upper and lower surfaces thereof.

It will be noted by reference to Fig. 5 in particular that the vertical recess 18 in the stock 10 is wider at its forward portion than it is at its rear. At the junction of the narrow and wide portions of the recess 18, each of the side-walls is formed with two forwardly-facing recoil-seats 19—19 respectively located adjacent the respective opposite sides of the recess 18. Inwardly of each of the seats 19, the material of the stock 30 is extended forwardly beyond the vertical plane of the adjacent recoil-seats 19 to provide a stabilizing-rib or lip 20, one of which latter is located adjacent each of the recoil-seats 19—19, and which act in a manner as will hereinafter appear to stabilize the respective opposite side-walls of the recess 18 in the stock 10.

The trigger-plate member 14 before referred to of the receiver-unit 11, is relatively narrow transversely at its rear portion and relatively wide at its forward portion to fit the respective narrow and wide portions of the vertical recess 18 in the stock 10. The said trigger-plate member is provided adjacent its rear end with a depending guard-loop 21 housing the finger-piece 45 of a trigger 22. The rear portion of the trigger-plate member 14 also mounts a firing mechanism which, however, requires no detailed description herein other than possibly to note that the said firing-mechanism includes a hammer 23, a sear 50 24 and a hammer-spring 25.

The relatively-wide forward portion of the trigger-plate member 14 is provided with a vertical magazine-receiving passage 26 adapted to receive a box-magazine (not shown) in a manner well known in the firearm art. On each of its respective opposite sides and about midway of its length, the trigger-plate member 14 is provided with one of two corresponding stabilizing-ribs or lips 27. Each of the stabilizing-ribs 27 just referred to, projects rearwardly and overlaps the outer face of the adjacent one of the stabilizing-ribs 20 of the stock 10, as is especially well shown in Fig. 2. Preferably, the rear face of each of the stabilizing-ribs 27 of the trigger-plate member 14 bears against the adjacent one of the forwardly-facing recoil-seats 19 of the stock 10. Preferably also, the forward face of each of the stabilizing-ribs 20 of the stock 10 also engages with the rear face of the adjacent wide front portion of the trigger-plate member 14 to assist in absorbing recoil shocks.

The central lug 17 of the trigger-plate member 14 is formed centrally at a point above the coupling-ribs 16—16 thereof, with an abutment-rib 28 having its forward face normally in engagement with the rear face of an integral web 29 extending transversely across the hollow interior of the receiver-member 13 adjacent the lower end and about midway the length thereof.

The respective rear portions of the members 13 and 14 may, if desired, be coupled to the stock 10 in a suitable manner such, for instance, as the manner shown in my co-pending application Serial No. 473,111, filed January 21, 1943.

When the firearm is discharged, the receiver-member 13 will, of course, violently recoil under the shock and such recoil will be transmitted to the trigger-plate member 14 by way of the web 29 of the receiver-member 13 and the abutment-rib 28 of the trigger-plate member 14. The recoil shocks thus received by the trigger-plate member 14 will, in turn, be transmitted by the rear faces of the stabilizing-ribs 27—27 and the adjacent portions of the trigger-plate member 14, to the stock 10.

When the recoil shocks are received by the stock 10 in the manner as above described, there is a natural tendency for the relatively-thin side-walls of the vertical recess 18 in the stock 10, to spread laterally outwardly and eventually to weaken the stock and cause the splitting thereof, unless such tendency is offset. The outward flexing of the side-walls of the recess 18 is prevented or so minimized as to be substantially harmless, by the engagement of the inner face of each of the stabilizing-ribs 27 of the trigger-plate member 14 with the outer face of the adjacent one of the two stabilizing-ribs 20 of the stock 10.

By means of the present invention, the tendency of the stock to split under the shock of recoil strains its overcome or minimized without requiring the use of special binding- or coupling-screws or the like passing laterally through the stock.

Thus, not only is the cost of such binding-screws obviated, but more space is left free in the firearm structure for the accommodation of various features of the firearm mechanism, magazine, etc.

The invention may be carried out in other specific ways than those herein set forth without departing from the spirit and essential characteristics of the invention, and the present embodiments are, therefore, to be considered in all re-

spects as illustrative and not restrictive, and all changes coming within the meaning and equivalency range of the appended claims are intended to be embraced therein.

5 I claim:

1. A firearm structure including in combination: a stock having an interior vertical longitudinal recess therein which is relatively wide at its forward end-portion and relatively narrow at its rear end-portion, the said stock being formed in each of the opposite side-walls of the said recess at the junction of its two said end-portions with one of two vertical stabilizing-ribs each having an outwardly-facing surface; a receiver-member extending into the upper part of the recess in the said stock; a trigger-plate member having a relatively-wide forward end-portion and a relatively-narrow rear end-portion respectively extending into the lower parts of the respective forward and rear end-portions of the recess in the said stock, the said trigger-plate member being formed on each of its respective opposite sides at the junction of its relatively-wide forward end-portion and its relatively-narrow rear end-portion with one of two vertical stabilizing-ribs respectively overlapping the adjacent one of the vertical stabilizing-ribs of the said stock, and each of the said vertical stabilizing-ribs of the said trigger-plate member having an inwardly-facing surface engaged with the outwardly-facing surface of the adjacent one of the said vertical stabilizing-ribs of the said stock to thereby hold the side-walls of the recess in the said stock against undue outward flexure; and coupling-means coupling the said receiver-member to the said trigger-plate member and constructed and arranged to transmit the rearward recoil shock of the said receiver-member to the said trigger-plate member.

2. A firearm structure including in combination: a stock having an interior vertical longitudinal recess therein which is relatively wide at its forward end-portion and relatively narrow at its rear end-portion, the said stock being formed in each of the opposite side-walls of its said recess at the junction of its two said end-portions with one of two vertically-extending and forwardly-projecting stabilizing-ribs each having an outwardly-facing surface; a receiver-member extending into the upper part of the recess in the said stock; a trigger-plate member having a relatively-wide forward end-portion and a relatively-narrow rear end-portion respectively extending into the lower parts of the respective forward and rear end-portions of the recess in the said stock, the said trigger-plate member being formed on each of its respective opposite sides at the junction of its relatively-wide forward end-portion and its relatively-narrow rear end-portion with one of two vertically-extending and rearwardly-projecting stabilizing-ribs, each of the last-mentioned stabilizing-ribs having an inwardly-facing surface engaging with the outwardly-facing surface of the adjacent one of the said vertical and forwardly-projecting stabilizing-ribs of the said stock to thereby hold the side-walls of the recess in the said stock against undue outward flexure; and coupling-means coupling the said receiver-member to the said trigger-plate member and constructed and arranged to transmit the rearward recoil shock of the said receiver-member to the said trigger-plate member.

DAVID M. WILLIAMS.
